W. W. Wallace, Superintendent of Public Schools of Maine

Letters, President,

The schedule referred to in these Letters Patent and making
part of the same containing a description in the words of the
said Rhodes Kingsbury himself of his improvement, being a
new bag or Bush for carrying shives in ships blocks and for
other purposes.

to all to whom these presents shall come

Be it known, that I, Wherry Thompson, of Bath in the County of Lincoln and State of Maine, have invented a new and useful improvement being a dove cog or bush for cogging thines in ships blocks and other similar articles and the application of the same to such cogs or bushes, for the purpose of fitting the same and that the following is a full and exact description of the construction, and fitting and operation of said machine as invented as improved by me,

The cog or bush is a cylinder, and its length is equal to the thickness of the shive, or thing to be cogged or bushed, and whose diameter is one sixteenth of an inch or there abouts longer than the diameter of the hole to be cogged or bushed. On the outside of the cog or bush, is cast or cut a screw by which the cog or bush is drawn into the shive, or thing to be cogged, and which fastens the cog to the shive, or in other words the cog or bush invented by me, is a screw whose length is equal to the thickness of the thing to be cogged, and of such size as to draw firmly into the hole of the shive or thing to be cogged and the invention consists principally in the application of the screw to cog for shives of ships blocks, but the same may be applied to cog or bush for other things. The invention is more particularly described in the drawing hereto annexed and in the patent No. 22, and No. 33, expressed "the screw cog

X 3489

invented by me. Fig 1st, Fig 2^d, & Fig 3^d are three B.B.B., are
screw cog, fitted to the shivs, screwed into them in the manner
of my invention C.C. are, screws or the threads of a screw, and
are cut on the rim of the cog, and which draw the cog into the
hole of the shivs. The screw cog or bush is intended generally
to be used for cogging shives of ships blocks of all kinds, and
other similar articles that run on iron pins or journals,
and can be made of iron or composition, either by casting or
working and cutting. It differs from the common cog or bush
in this, that it has a plate, and does not require riveting to
the shivs, the common cog is sunk the thickness of the plate
into the shivs, and the plate being about one third of the
circumference of the shivs and about a third of its thickness
and in a triangular form is riveted through the shivs at
the angles, the method of letting the plate cog into lignum-
vitae, is difficult, the wood being hard, it is almost im-
possible to let them in tight, they soon wear loose and become
useless, the plate being let in on one side of the shivs tends
to cant the shivs on the shell of the block, as the strain comes
on one side of the shivs; the shivs is necessarily cut so
thin to receive the plate that the rivets have but little
support, they often crack the shivs and render it useless
or become loose, and a shiv once cogged in this way, cannot
again, be cogged. The following are some of the advantages
of the screw cog, or bush, as invented by me. It has no
plate to weaken the shivs, it requires no riveting but can be
screwed into the hole of the lignum-vitae shivs, the hole being
bored about one sixteenth of an inch smaller than the
cog, the threads of the screw cutting into the shivs so that
they become perfectly firm & tight and stationary and will
not wear loose. The screw cog can be made with as
little expense as the common plate cog, and can be fastened
to the shivs with small stiff screws. It is a great im-
provement in cogging.

onto the shiv with a square steel scanner, now in common use for running out iron copper. The screw cog can be applied to all the shivs in all the blocks of the ship, whereas the plate cog can only be applied to shivs of the larger size; it may also be applied to shivs whose pin holes have been worn so large as to be unfit for use, and to such as have had their pin holes worn oblong and thus become useless. - But the principal advantage of the screw cog is the saving of expense. It can be fitted to the shiv for less than one fourth part of the expense of fitting the plate cog.

What I claim as new and as my own invention or discovery in the above described Machine, and for which I ask an exclusive privilege, is the screw cog or bush for shivs and other articles, and the application of the screw to the cog or bush for fitting the same to shivs and other articles.
